UNITED STATES PATENT OFFICE.

WILLIAM H. MOON, OF MUNCIE, INDIANA.

BLOWPIPE-REST.

SPECIFICATION forming part of Letters Patent No. 740,455, dated October 6, 1903.

Application filed January 13, 1903. Serial No. 138,937. (No model.)

To all whom it may concern:

Be it known that I, WILLIAM H. MOON, a citizen of the United States, residing at Muncie, in the county of Delaware and State of Indiana, have invented a new and useful Blowpipe-Rest, of which the following is a specification.

My invention is an improvement in blowpipe-rests, the object of my invention being to provide a suitable support for glass-blowers, especially those engaged in the manufacture of window-glass. The rest is designed to be placed on the beam of a small swinging crane arranged directly in front of a furnace. When a cylinder of glass has been blown, it usually presents an irregular surface. It is therefore passed into the furnace, the weight of the cylinder being supported by my rest, which comprises two ball-bearing wheels mounted tandem-like, the cylinder resting between the wheels. By revolving the cylinder at a red heat it soon becomes of a uniform diameter, the irregularities disappearing. With the old solid fork it was difficult to turn the cylinders, which are of considerable weight.

In the accompanying drawings, Figure 1 is a perspective view of my rest. Fig. 2 is a side elevation, parts being in section. Fig. 3 is a sectional view taken transversely through one of the rollers, the axle and balls being in elevation.

In carrying out my invention I employ a bracket having a stem A, carrying at its upper end a solid horizontal plate B, having sides B', from which project upward from each end of a side two sets of parallel arms B², these arms being rounded and thickened at their upper ends. A web B³, formed centrally on the upper part of the plate, connects the two sides, which have a curved upper surface between the arms. The thickened upper portion of the arms is transversely perforated and threaded, the perforations on one side of the rest being of greater diameter than those in the arms on the opposite side. An axle C, having a threaded end and head and a smooth intermediate portion, connects the front and rear arms, respectively, the head fitting in the larger perforation. An interiorly-threaded collar C' is secured on the

threaded end portion of the axle and fits tightly against the inner face of the arm on that side. This collar is cut out at C² adjacent its inner edge. A similar non-threaded collar C³ is positioned on the smooth portion of the axle adjacent the head and is held against rotation by a lug C⁴, projecting into a recess C⁵, formed in the arm B².

It is understood that the above description of the collars secured on one of the axles applies to those on the other collar.

On each axle between the collars is mounted a wheel D, and each wheel has an annular groove D', the upper edge of the groove projecting outward and forming a flange D², which encircles the inner cut-out edge of the collars, a groove and flange being formed on each side of the wheel. Within the grooves held between the wheels and the collars are the antifriction-balls E.

The parts A and B are cast in one piece, and the wheels are formed with a hard chilled surface to enable them to withstand the intense heat imparted to them by the glass.

When all the parts described are assembled together, they are held in place by a nut E', threaded on the end of each axle.

Having thus fully described my invention, what I claim as new, and desire to secure by Letters Patent, is—

1. A blowpipe-rest comprising a bracket having a downwardly-projecting stem, two pairs of upwardly-extending arms, each pair of arms carrying a non-revolvable axle, a roller mounted on each, collars on each side of the rollers, and antifriction-balls between the collars and their respective roller.

2. A blowpipe-rest comprising a bracket having a stem, a plate at the upper end of the stem, arms projecting upward from each corner of the plate, said arms having threaded perforations therein, axles threaded adjacent each end secured in the perforations of the arms and having a smooth intermediate portion, rollers mounted thereon, collars on each side of said rollers, and antifriction-balls between the rollers and collars.

3. A device of the kind described, comprising a bracket having recesses, axles having threaded heads and ends mounted in the bracket, rollers having annular grooves on

each side and an outwardly-extending flange around the grooves, interiorly-threaded collars on the threaded end portions of the axles having their inner edges cut away, collars on the smooth portion of the axles, lugs on said collars projecting into the recesses, the said rollers being mounted on the axles between

the collars, and antifriction-balls arranged in the grooves of the rollers and held in position by the collars and flanges.

WILLIAM H. MOON.
